UNITED STATES PATENT OFFICE.

FRANK M. JOSLIN, OF AMSTERDAM, NEW YORK, ASSIGNOR TO INMAN MANUFACTURING COMPANY, INC., OF AMSTERDAM, NEW YORK, A CORPORATION OF NEW YORK.

CUTTING MACHINE.

1,417,830.

Specification of Letters Patent. Patented May 30, 1922.

Application filed March 29, 1920. Serial No. 369,485.

To all whom it may concern:

Be it known that I, FRANK M. JOSLIN, a citizen of the United States, and residing at Amsterdam, Montgomery County, State 5 of New York, have invented certain new and useful Improvements in Cutting Machines, of which the following is a specification.

This invention relates to certain detailed improvements in cutting machines of the 10 type in which a reciprocating cutter is employed. The object of the invention is to provide a construction in which a slideable cutter carrier is mounted in a suitable dovetailed guideway, one side of which guideway 15 is adjustable toward and from the other; to provide a carrier having a hollow projection for receiving the operating means, and having beneath such projection a rib which is attached to the body of the carrier and the 20 projection, this arrangement being such as to produce a strong and rigid construction for receiving the thrust of the cutter; and to provide certain other detailed improvements by which the machine is rendered 25 more efficient and serviceable for the purpose intended.

The invention is illustrated in the accompanying drawings, in which—

Fig. 1 is a front elevation of the machine; 30 Fig. 2 is a side elevation at right angles to that of Figure 1;

Fig. 3 is a horizontal sectional view on the line 3—3 of Figure 2; and

Fig. 4 is a vertical sectional view on the 35 broken line 4—4 of Figure 1.

Referring to the drawings in detail, 1 shows a hollow standard which serves to support the various parts of the mechanism. A frame 2 is rigidly mounted upon 10 the upper part of this standard, and is secured thereto by any suitable means such as bolts 3. The front part of this frame is provided with a guideway in which a cutter carrier 4 is adapted to reciprocate, one side of 15 said guideway being formed by a flange 5 of said frame and the other by an angular member 5^a, which is adjustably secured to the frame by means of bolts 6. The angular member 5^a may be adjusted toward and from 20 the opposite side 5 of the guideway by means of set bolts 7. The construction just described provides a dovetailed guideway in which the carrier 4 is intended to reciprocate, this carrier being shaped to fit the 25 guideway.

Extending outwardly from the carrier 4 is a hollow boss or projection 8 adapted to receive a pin 9, which is connected to a reciprocating rod 10, which rod is given a reciprocating motion by means of eccentric 60 mechanism 11 mounted in the base of the standard 1. The eccentric mechanism is operated from a shaft 12 to which any suitable source of power 13 is attached. A clutch mechanism 14 controlled by a handle 65 15, is provided for connecting the shaft 12 to the source of power 13.

Below the hollow projection 8 heretofore referred to, the cutter carrier is provided with a rib 16 which is integrally connected 70 with the body of the carrier and with the hollow projection, this rib lying immediately beneath such projection. A cutter 17 is secured to the lower end of the rib 16. This construction provides a means by which the 75 cutter is mounted directly beneath the point at which the power is applied to operate the cutter carrier, and the rib 16 being rigidly secured to the carrier and to the projection in which the operating means is mounted, 80 it will be seen that a strong and rigid construction of cutter carrier is provided.

A fixed cutter is arranged to cooperate with the movable cutter 17, this fixed cutter being formed by a plate 18 slotted as at 19 85 through which set screws 20 project and engage a fixed part of the frame, this construction providing means by which the plate 18 may be adjusted toward and from the cutter 17. A guard plate 21 is arranged 90 to overlie the plate 18 adjacent the line of movement of the cutter 16, this guard plate being spaced from the plate 18 a sufficient distance to permit the material being cut to be pushed thereunder. The plate 18 95 forms part of a work supporting platform, over which the material advances in passing to the cutter, and mounted in line with said plate 18 is a table 22 adapted to support the work, this table being held in position 100 by a suitable brace 23. An adjustable work gauge 24 is secured to a rigid part of the machine against which the material is adapted to be placed at the time of the cutting operation, this gauge serving to determine the length of the pieces to be cut from the material. A chute 25 is arranged in position to receive the several pieces of material.

It will be apparent from the foregoing 110

description that the hollow projection 8 affords a good bearing in which the operating shaft or pin 9 can be mounted, and that the rib 16, secured to said projection and to the body of the carrier, serves to brace the projection against the thrust of the cutter during the cutting operation, the arrangement as a whole providing a strong and rigid construction. The particular shape and arrangement of the cutter carrier and guideway are also such as to produce a strong and serviceable construction, and one in which accurate adjustment of one side of the guideway may be made to compensate for wear of the parts.

What I claim as my invention and desire to secure by Letters Patent is:

1. A machine of the class described comprising a frame having a vertically arranged guide way, a cutter carrier slidably mounted in said guide way, said carrier having a hollow boss extending laterally therefrom beyond said frame, a rib arranged beneath said boss at right angles to the front face of the carrier and integrally connected with said boss and with said carrier, a cutter secured to the lower edge of said rib and arranged substantially in a vertical plane passing through the axis of said boss, a reciprocating member arranged at the rear of said carrier for operating the same, and means mounted in said boss and engaging said reciprocating member.

2. A machine of the class described comprising a frame having a vertically arranged guide way, a cutter carrier slidably mounted in said guide way, said carrier having a hollow integral boss extending laterally therefrom beyond said frame, a rib arranged beneath said boss and integrally connected

therewith and with said carrier, a cutter secured to the lower edge of said rib and arranged substantially in a vertical plane passing through the axis of said boss, a work receiving platform arranged at right angles to said cutter, part of said platform being adjustable toward and from the line of movement of the said cutter, the end of said adjustable part forming a stationary cutter cooperating with the cutter on said carrier, a reciprocating member arranged at the rear of said carrier for operating the same, and means mounted in said boss and engaging said reciprocating member.

3. A machine of the class described comprising a frame having a vertically arranged guide way on one face thereof, a cutter carrier slidably mounted in said guide way, said carrier having a hollow boss extending laterally therefrom beyond said face of the frame, a rib arranged beneath said boss and integrally connected therewith and with said carrier, a cutter secured to the lower edge of said rib and arranged substantially in a vertical plane passing through the axis of said boss, a work receiving platform arranged on one side of the plane of movement of said cutter, the end of said platform beneath said cutter being arranged to cooperate with said cutter to cut material on said platform, an adjustable work gauge for determining the length of material to be cut, arranged on the other side of the plane of movement of said cutter, a reciprocating rod arranged at the rear of said cutter carrier and a pin passing through said boss and engaging said rod whereby said cutter is reciprocated.

In testimony whereof I affix my signature.
FRANK M. JOSLIN.
